United States Patent Office

Des. 185,480
Patented June 9, 1959

185,480

FORK OR SIMILAR ARTICLE OF FLATWARE

John P. Young, Bronxville, N.Y., and Charles A. Arnold, Providence, R.I., assignors to Lyon Incorporated, Detroit, Mich., a corporation of Delaware

Application April 22, 1958, Serial No. 50,579

Term of patent 14 years

(Cl. D54—12)

Fig. 1

Fig. 2

The essential features of our design reside in the handle portion shown in the full lines on the drawing.

We claim:

The ornamental design for a fork or similar article of flatware, substantially as shown and described.
